UNITED STATES PATENT OFFICE.

WILLIAM R. CANNON AND ELMER DAVIS, OF OKMULGEE, OKLAHOMA, ASSIGNORS TO BAKER BROTHERS GLASS COMPANY, OF OKMULGEE, OKLAHOMA, A CORPORATION OF INDIANA.

CAPPING HORSE.

Application filed February 13, 1925. Serial No. 8,950.

To all whom it may concern:

Be it known that we, WILLIAM R. CANNON and ELMER DAVIS, citizens of the United States, residing at Okmulgee, in the county 5 of Okmulgee and State of Oklahoma, have invented a new and useful Capping Horse, of which the following is a specification.

The object of our invention is to provide an improved capping horse unit capable of 10 automatic co-operation with a drawn glass cylinder which is somewhat variable in shape.

The accompanying drawings illustrate our invention.

Fig. 1 is a side elevation of a capping horse embodying our invention, with a cylinder in place thereon;

Fig. 2 is an end elevation of one of the units;

Fig. 3 is a side elevation;

Fig. 4 is a plan on a larger scale.

In the drawings 10 indicates a standard provided at its upper end with a cross arm formed of two parallel spaced boards 11, 11 25 conveniently held in spaced relation by laterally spaced spacers 12 forming vertical pockets 13, 13, 13. In the middle space 13 we mount a vertically slideable finger 14 and in each of the end pockets 13 we mount a vertically slideable finger 15. Finger 14 is provided near its lower end with a cross pin 16 and each of the fingers 15 is provided with a cross pin 17.

The spacers 12 extend below arms 11 far enough to form supports for a pivot pin 18 upon each of which is pivoted a rocker arm 19, one of said arms lying beneath and engaging pin 16 and pin 17 of the outer finger 15 and the other engaging pin 16 and pin 17 of the inner finger 15, the arrangement being such that the three fingers 14, 15, 15 are supported upon the two rocker arms 19, 19 and balanced against each other, finger 14 rising upon depression of fingers 15, and fingers 15 rising upon depression of finger 14. The group of fingers thus forms a transverse hammock.

The upper end of the three fingers 14 and 50 15 are preferably arc shaped to approximate the curvature of the cylinders C to be supported.

Each of the units described above is conveniently provided at its lower end with a downwardly projecting toe 20 which may

be inserted in a suitable pocket 21 in the 55 floor and at its upper end is provided with an upwardly projecting finger 22 adapted to be retained in a pocket or slot 23 formed in a bracket 24 carried by a stretcher bar 25 suitably braced by braces 26, the arrangement being such that the units may be arranged in a series, as shown in Fig. 1, and laterally spaced by placement in appropriate brackets 24 and pockets 21, the parts being so proportioned that, by lifting toe 20 60 from a pocket 21, the unit may be readily swung outwardly and retracted downwardly from bracket 24 and replaced at another point by a reverse operation.

In use the fingers 14 and 15 of any particular unit automatically adjust themselves to irregularities of a cylinder when the same is placed thereon.

By reason of the inverted L-shaped form of the unit ample foot-room is provided for 75 the capper operating along the right hand side of Fig. 2 and, by reason of the ready removal of each unit, the horse may be quickly arranged for proper support of a cylinder to be cut in desired sections of different 80 lengths.

We claim as our invention:

1. A capping horse unit comprising a support, a group of vertically movable fingers forming a transverse hammock, and inter-connections between said fingers whereby movement of one of said fingers in one direction will cause movement of other of said fingers in the opposite direction. 85

2. A capping horse comprising a plurality 90 of spaced units each unit forming a transverse hammock and comprising a support, a transverse group of vertically movable fingers, and inter-connections between said fingers whereby movement of one of said fingers in one direction will cause opposite movement of other of said fingers. 95

3. A capping horse unit comprising an inverted L-shaped standard, a plurality of vertically slideable fingers mounted in the 100 horizontal element of said standard so as to form a transverse hammock, and inter-connections between said fingers whereby movement of one of said fingers in one direction will cause movement of another of said fingers in the opposite direction. 105

4. A capping horse comprising a plurality of inverted L-shaped supports laterally

spaced, a transverse group of vertically movable fingers carried by the horizontal arm of each of said supports, and inter-connections between said fingers whereby movement of one finger in one direction will cause movement of another finger in the opposite direction.

5. A capping horse unit comprising a standard, a cross arm supported by said standard, three fingers vertically slidable on said cross arm and together forming a transverse hammock, and a pair of rocker arms engaging said fingers in pairs, substantially as described.

15 6. A capping horse comprising a plurality of spaced brackets 24, and a plurality of supporting units each comprising a transverse hammock, a supporting standard therefor, and means detachably co-operative with any one of the brackets 24, whereby a group of said units may be variably associated in laterally spaced arrangements to

form a continuous support for a drawn glass cylinder.

7. A capping horse comprising a stretcher 25
bar, a plurality of brackets 24 carried by
said stretcher bar, and a plurality of ham-
mock units each comprising a vertical stand-
ard, a cross arm, means adjacent the junc-
tion of said standard and cross arm, for de-
tachable co-operation with any one of the
brackets 24, a plurality of vertically movable
fingers carried by the cross arm and inter-
connections between said fingers whereby
movement of one in one direction will cause
movement of another in the opposite direc-
tion. 35

In witness whereof, we have hereunto set our hands at Okmulgee, Oklahoma, this 13th day of January, A. D. one thousand nine hundred and twenty five. 40

WILLIAM R. CANNON.
ELMER DAVIS.
